UNITED STATES PATENT OFFICE.

GEORGE W. FOSTER, OF PROVIDENCE, RHODE ISLAND, ASSIGNOR TO UNIVERSAL WINDING COMPANY, OF BOSTON, MASSACHUSETTS, A CORPORATION OF MASSACHUSETTS.

CONE-WINDING MACHINE.

1,324,889.

Specification of Letters Patent. Patented Dec. 16, 1919.

Original application filed July 3, 1917, Serial No. 178,393. Divided and this application filed February 28, 1918. Serial No. 219,609.

To all whom it may concern:

Be it known that I, GEORGE W. FOSTER, a citizen of the United States, residing at Providence, in the county of Providence, 5 State of Rhode Island, have invented certain new and useful Improvements in Cone-Winding Machines, of which the following is a specification.

My invention relates to winding machines 10 and particularly to cone-winders of the drum- or friction-driven type. Such a type of machine is shown in my pending application, Serial No. 178,393, filed July 3, 1917, from which this application is divided, and 15 the present improvements are directed particularly to the means for supporting the cone-tube or holder for the package to adapt it to recede from the driving-drum or roll as the winding increases in diameter. One 20 object of the invention described in my previous application is to build the cone with a gradually increasing taper on its surface from its interior to its exterior, and for this purpose it is necessary that the cone-tube or 25 holder be held at its ends to allow its axis to be displaced in angular relation to the surface of the driving-roll or drum. That 30 is to say, as the cone increases in diameter the taper of its surface becomes steeper in pitch, and therefore the cone-holder must rock axially to maintain the surface of the 35 cone constantly in contact with the surface of the drive-roll. Further features of the present improvement consist in a simplification 40 of the structure of the cone-supporting mechanism, and particularly in providing means for rendering its operation more convenient of control in preparing the machine for winding and in doffing the completed package.

The manner and means for carrying out these improvements are fully described in the following specification, illustrated by the accompanying drawings, in which like reference characters designate like parts. In the drawings:—

Figure 1 is a side elevation of the essential elements of the winding-mechanism for one unit of a winding machine;

Fig. 2, a sectional view through the axis of the cone-tube or holder showing the manner in which it is held by its end-supports;

Fig. 3, a plan view of the cone-holder supporting-devices;

Fig. 4, a part sectional view showing the 55 means for pivotally supporting the cone-holder arms; and

Figs. 5 and 6, detail views of the same.

Referring first to Fig. 1, D designates 60 the friction drive-roll or drum which is supported and rotated by a horizontal shaft R journaled in suitable bearings on the machine-frame, not herein shown. Usually the shaft R extends the whole length of the machine and carries a series of drive-rolls D, one for each winding unit. Arranged opposite and parallel with the shaft R is a longitudinally-reciprocable traverse-bar E which is supported to slide in suitable bearings, not herein shown, on the machine frame. The traverse-bar E carries a plurality of thread-guides G, one for each winding unit, which are reciprocated thereby to traverse the thread longitudinally of the cone or package in the usual manner as 75 well known in the art. Preferably, the guides G are formed of sheet-metal with portions straddling the bar E and fastened thereto by suitable means such as the screws 76. Each guide G has an arm 77 reaching 80 inwardly toward the surface of the driving-drum D, said arm being bent upwardly at its end and formed with a slot g through which the thread or yarn y leads to the package.

At the rear of the shaft R, and extending parallel therewith, is a tie-rod T which extends the length of the machine between its end-frames as shown more particularly in my previous application above referred to. 90

The rod T forms the principal support for the pivoted arms which carry the cone-holders at their outer ends, and usually the machine is constructed with winding units on both sides of the central tie-rod T in double-gang form. That is to say, each machine has two parallel shafts R arranged in spaced relation below and on opposite sides of the tie-rod T, and the arms for the cone-holders extend from the center of the machine out- 95

wardly in opposite directions to bring their ends into proximity with the several driving-drums D, D on the shafts. Spaced at intervals along the rod T are a plurality of depending arms or brackets 28 which support a lower, parallel rod T', see also Figs. 4 and 5. The brackets 28 are extended below the rod T' and secured therein are pins 100

105

or studs 29 on which are pivotally mounted the swinging arms A for supporting the small ends of the cone-tubes or mandrels C on which the packages are wound, see 5 Figs. 3 and 4. The opposite or base end of each cone-tube C is supported by an arm B which is pivoted on the rod T'. Through this arrangement the larger or base end of the cone is caused to swing about an axis ele- 10 vated above the axis of the pivot about which the small or apex end swings in the manner as later described. Each arm B is formed with a hub 30 which is rotatable on the rod T' and free to slide therealong 15 against the tension of a coiled spring 31. As shown in Figs. 3 and 4, the arms B, B' are arranged in pairs disposed in opposite relation between each pair of brackets 28. The arm B of each pair supports the base 20 end of the cone-tube C on one side of the machine while the other arm B' extends in the opposite direction to support the cone-holder on the other side of the machine. The arms B and B' are located in position 25 longitudinally of the rod T' by means of collars 32 secured to the rod T by set-screws 33. Each collar 32 is formed on its side with an inclined cam-face 34 against which a lug 35 on the hub 30 of the arm B rides, 30 see detail view Fig. 6. The lug 35 is formed on the side of a flange 36 at the end of the hub 30, and bearing against the opposite side of the flange is a plate or washer 37 which takes the thrust of the spring 31. 35 The washer 37 is formed with spaced arms 38, 38, see Fig. 5, which straddle the sides of the upper rod T to hold the washer from turning. As shown in Fig. 4, the spring 31 acts against the hubs 30 of both arms B 40 and B' to maintain their lugs 35 bearing against the cam-faces 34, and the purpose of the washers 37 is to prevent the swinging movement of the arm B from tending to wind or unwind the spring 31. The arms 45 B, B' are caused to swing upwardly on the rod T by the recession of the cone-holders C from the drive-rolls D during the growth of the package, see Fig. 1. As the arm B swings upwardly about the axis of the rod 50 T' the lug 35 will ride outwardly on the inclined cam-face 34 of the collar 32 to slide the arm bodily to the right, as viewed in Fig. 4, against the action of the spring 31. Likewise, the upward movement of the arm 55 B' will cause its lug 35 riding on the incline 34 of its related collar 32 to slide the arm to the left on the rod T'. Through this arrangement the cone-holders C are caused to be displaced longitudinally of their respective drive-rolls in a substantially axial direction. This axial displacement of the cone is in the direction of its apex end and is relatively slight, being designed to overcome the tendency of the cone to build up 60 with an excessive concavity at its nose. This

tendency arises from the inclined relation of the axis of the cone to the surface of the drive-roll and in the present type of machine this inclination becomes greater as the cone builds up with an increasing taper on its sur- 70 face. The purpose of the above described arrangement for shifting the cone along its drive-roll is more fully explained in my pending U. S. application for patent, Serial No. 124,373, filed Oct. 7, 1916, the present 75 mechanism embodying certain improvements in the structure and method of operation of the device.

Referring to Figs. 3 and 4, the apex or nose end of each cone-holder C is supported 80 at the end of the before-mentioned arm A, which carries a bearing arranged as follows: Pivoted on the stud 29 which projects from the side of the bracket 28 is a hub 40 held between the side of the bracket and a cap-like bearing 41. The cap 41 is formed with a nut 42 screwed onto the reduced end 43 of the stud 29 and locked in place by a check-nut 44. The inner face of the cap 41 is concaved to receive a relatively thin, 85 dished spring-washer 45 which bears against the side of the hub 40, thereby tending to regulate the swinging movement of the arm A about its axis. That is to say, the spring 45 acts to frictionize the turning of the hub 40 on the stud 29 and thereby serves to resist the movement of the arm A as the nose of the cone recedes from the drive-roll. The purpose of this arrangement is to insure a firm contact of the nose end of the cone 90 against the drive-roll D which imparts rotation thereto. As shown more particularly in Fig. 3, the hub 40 is formed with a short arm 46 to the side of which is hinged the main arm A. The arm A is connected to 105 the arm 46 by a pivot-pin 47 and is formed with a pocket 48 for receiving the end of a helical spring 49. The opposite end of the spring 49 bears against the side of the short arm 46 to maintain the end of the main arm 110 A in position to receive the apex or tip of the cone-holder C, while also providing for the axial displacement of the cone when the arm B is slid along the rod T', as previously explained. As shown in Figs. 3 and 4, each 115 stud 29 supports a pair of hubs 40 for two oppositely extending arms A, A', the latter supporting the cone-holders of two winding units on opposite sides of the machine.

Referring now particularly to Fig. 2, the 120 cone-holder C here shown is of conventional form consisting of a conical tube having relatively thin walls, usually of paper or fiber, converging at one end in the rounded nose c. The nose c is adapted to fit into a 125 cup-like member 50 mounted in a ball-bearing at the end of the arm A. Any suitable form of bearing may be employed for this purpose and as here shown the cup 50 carries a ball-race 51 on its periphery adapted to re- 130

ceive a series of balls 52 rolling in a corresponding race 53 which is held in an opening 54 in the end of the arm A. The opposite, base end of the cone-tube C fits over 5 the tapered periphery of a ring or bearing 55 which is formed with a hub 56 carrying a ball-race 57. Projecting from the side of the arm B is a stud 58 formed with a head 59 having its inner side concaved. The stud 10 58 is inserted through the bore 60 of a sleeve 61, the outer end of which is of convex formation to adapt it to fit the concavity of the head 59. The inner end of the sleeve 61 is slightly enlarged in a flange 15 62 having its side formed convexly to adapt it to fit into a corresponding concavity 63 in the arm B. On the periphery of the sleeve 61 is a ball-ring or race 64 arranged opposite the race 57 with the balls 66 20 revolving therebetween. A cap 67 is screwed onto the sleeve 61 to hold the race 64 in place against a shoulder 68, said cap being formed with a flange 69 for retaining the bearing-ring 55 in position with the balls 25 66 in proper relation to the races 57 and 64. It will be noted that the bore 60 of the sleeve 61 is of greater diameter than that of the stud 58 to provide sufficient clearance for the sleeve to rock slightly on its 30 bearing. That is to say, the sleeve 61 which carries the bearing-ring 55 is free to move in the manner of a ball-and-socket joint, the purpose of the arrangement being to allow the cone C to change its angle of inclination to the driving-drum D as it recedes therefrom with the growth in the winding.

Referring now to Figs. 1 and 3, the arm B is slotted along its top at 70 and pivoted 40 in the slot on a cross-pin 71 is a lever 72. The outer end of the lever 72 is provided with a finger-piece 73, while its inner end is formed with a hook 74, the extremity of which normally rests on the top of the 45 tie-rod T. As the arm B swings upwardly during the building of the cone the end of the hook 74 rides around the periphery of the rod T without interfering with the movement of the arm. When, however, it is 50 required to raise the cone away from contact with the drive-roll D, in piecing up the yarn or in applying the cone-tube C to its holder and in doffing the completed package, the arm B is lifted far enough to allow 55 the end of the lever 72 to hook around the rod T. Through this means the arm B may be suspended in raised position to facilitate the application of the cone-tube C to the supporting arms A and B and the 60 removal of the completed package; and by pressing down on the outer end of the lever 72 its hook 74 can be released to allow the arm to be lowered into operative position as shown in Fig. 1. A weight W, shown 65 in Fig. 1, is usually attached to the side of

the arm B to maintain the cone or package firmly against the surface of the drive-roll D during the winding, this element being omitted from Fig. 3 so as not to confuse the showing of the other parts.

The method of operation of my improved apparatus is as follows: The paper cone-tube C is applied to its supporting arms A and B by inserting its rounded nose c into the bearing-cup 50 and fitting its base end 70 over the conical bearing-ring 55, see Fig. 2. The hinged arrangement of the arm A adapts it to yield to provide for slipping the cone-tube onto the supporting-ring 55, and when released the spring 59 causes it 75 to press against the nose end of the tube to hold its base end snugly in place on the ring. During the operation of applying the cone to its supports the arm B may be suspended in raised position, if desired, by 80 hooking the end of the lever 72, shown in Fig. 4, around the tie-rod T. After the cone-tube is in place the lever 72 is released to allow the arm B to drop, and the tube will then come down into operative 85 position against the surface of the drive-roll D.

The yarns y to be wound into the cones are supplied from suitable bobbins, usually arranged below but not herein shown, and 90 each yarn is generally led through suitable tension and stopping-devices, not herein illustrated, as they form no part of the present invention. Thence the yarn y leads through the slot g in the thread-guide G 100 and is secured to its cone-tube C by winding the end therearound. The threading up of the yarn may be effected while the arm B is held suspended by the hook-lever 72, if desired, this being the preferred practice 105 as more convenient for attaching the end of the yarn to the cone-tube.

The machine is now ready for winding, and each unit is started separately through the operation of suitable manually-controlled devices, not herein shown. The operation of the starting-devices causes the rotation of the shaft R and also the longitudinal reciprocation of the traverse-bar E 110 which is driven from a cam or other mechanism, not herein illustrated. The drive-roll D is rotated from the shaft R, and through its frictional contact with the surface of the cone-tube C the latter will be turned to wind on the yarn while it is being traversed longitudinally of the tube by the guide G. As the yarn builds up on the cone-tube C the increase in diameter of the mass causes the axis of the cone to recede from the drive-roll D while its surface remains constantly 115 in contact therewith. As the cone rises its supporting arms A and B swing upwardly on their pivots 29 and T', and meanwhile the axis of the cone becomes more and more inclined to the face of the drive-roll D due 120 125 130

to the increase in taper on the surface of the cone which is effected by the traverse-regulating mechanism of the machine shown and described in my previous application herein 5 first referred to. During this change in the inclination of the axis of the cone, the ring 55 which supports the base end of the tube C will rock slightly on its bearings as provided for by the ball-and-socket joints of 10 the bearing-hub 62 and the clearance of the stud 58 in its bore 60, see Fig. 2. The increase in inclination of the cone with respect to its drive-roll tends to cause its base to be formed convexly and its opposite end concaved. To prevent this tendency from causing 15 abnormal concavity at the nose end of the cone, whereby its structure will be weakened, the whole cone is shifted bodily to the right, or in the direction of its apex, 20 by means of the cam 34 on the collar 32, see Figs. 4 and 6, acting against the lug 35 on the flange 36 of the arm B as previously explained. Through this arrangement the 25 shaping of the cone is determined and controlled within the prescribed limits to provide the preferred formation of its ends.

The winding of the individual cones is usually arrested automatically by the action of suitable stopping-mechanism, a preferred 30 form of the same being illustrated in my pending application previously referred to. This stopping action is accomplished by lifting the cone bodily away from the drive-roll so that the driving action will cease, 35 and for convenience in repairing or piecing up a broken end the cone may be raised still further by hooking the lever 72 around the tie-rod T as previously explained. The rotation of the cap may be arrested manu- 40 ally in the same manner by shifting the stopping-devices or by lifting the arm B upwardly and hooking the lever 72 around the tie-rod T. After the cone has reached 45 its predetermined diameter the winding may be arrested by suitable sizing-devices which are engaged by the surface of the cone to cause actuation of the stopping-mechanism. The completed cone or package is removed from its supports by simply 50 pressing it bodily in the direction of its apex. This action causes the arm A to be swung on its pivot 47 against the action of the spring 49 and allows the base end of the cone-tube C to be slipped off from its bearing-ring 55 and its rounded apex end removed from the cup-member 50. Through 55 this arrangement the package may be very conveniently and expeditiously doffed and a new cone-tube applied for preparing the 60 machine to continue its operation.

It will be noted that the whole mechanism for supporting the cone-tubes is extremely simple in construction, comprising a minimum number of parts and with its elements 65 arranged to provide for the most convenient

manipulation in applying the cone-tubes and doffing the packages. Furthermore, my improved arrangement of the cone-supporting means provides for the tilting of the cone during its growth as its surface increases in 70 taper to maintain the proper driving contact between the cone and its drive-roll. The ball-bearings which support the ends of the cone-tube provide for a smoother and easier running of the package, thereby decreasing 75 the slippage between the surface of the cone and the drive-roll whereby to improve the character of the winding and to also prevent undue friction or abrasion of the yarn being wound.

Various modifications might be made in the form and construction of the parts of my improved apparatus without departing from the spirit or scope of the invention; therefore, without limiting myself to the 85 exact embodiment shown and described, what I claim is:—

1. In a cone-winding machine, the combination with a rotating drive-roll and a traversing thread-guide, of means to support the cone to be driven from the drive-roll comprising two opposite independently-movable pivoted arms, a cup-member rotatably mounted on the end of one of the arms to adapt it to receive the apex-end of the cone-tube on which the cone is wound, and a tapered ring rotatably mounted on the end of the other arm and adapted to enter the base end of the cone-tube to hold the apex of the latter in the cup-member. 100

2. In a cone-winding machine, the combination with a rotating drive-roll and a traversing thread-guide, of means to support the cone to be driven from the drive-roll comprising two opposite independently-movable pivoted arms, of ball-bearings mounted at the outer ends of said arms, a cup-member journaled in the ball-bearings on one of the arms to adapt it to receive the apex-end of the cone-tube on which the 110 package is wound, and a ring journaled on the ball-bearings on the other arm to adapt it to enter the base of the cone-tube to rotatably support the latter with its apex-end held in the cup-member. 115

3. In a cone-winding machine, the combination with a rotating drive-roll and reciprocable thread-guide, of means for supporting the cone-tube to adapt it to be driven from the drive-roll comprising two opposite independently-movable arms pivoted to swing away from the drive-roll, a tapered ring mounted on ball-bearings at the end of one of the arms to adapt it to rock slightly in relation thereto, and a cup-member mounted in ball-bearings at the end of the opposite arm to adapt it to receive the apex-end of the cone-tube while the base end of the latter is held on the ring. 120

4. In a cone-winding machine, the com- 125

- bination with a rotating drive-roll and a traversing thread-guide, of a pair of independently-movable hinged arms for supporting the cone to adapt it to be driven 5 from the drive-roll while allowing its axis to recede therefrom, a member mounted at the end of one of the arms with a ball-and-socket joint to adapt it to rock axially thereon, a bearing carried by said member, a ring 10 rotatable on said bearing and adapted to support the base-end of the cone-tube, and a cup-member rotatably mounted at the end of the other arm to adapt it to receive the apex-end of the cone-tube.
- 15 5. In a cone-winding machine, the combination with the rotating drive-roll and traversing thread-guide, of a pair of independently-movable hinged arms for supporting the cone to adapt it to be driven 20 from the drive-roll, a stud at the end of one of the arms formed with a head having an inner concaved seat, a sleeve-member having a bore fitted loosely to the stud and convex ends, one of which engages the concaved head of the stud and the other a concaved seat on the arm, a bearing supported by said sleeve, a ring journaled on said bearing to adapt it to rotatably support the base-end of the cone-tube, and a cup-member 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950
- the arm, a member mounted on said stud to adapt it to rock in relation to the axis thereof, a ball-race carried by said member, a ring-member for supporting the end of the cone-holder, a ball-race on said ring-member, and a series of balls rotatable between the ball-races.
10. In a cone-holder support for winding machines, the combination with a hinged arm, of a stud projecting from the side of the arm, a sleeve mounted on the stud to adapt it to rock axially thereof, a ball-race on the periphery of the sleeve, a bearing-member for the cone-holder, a ball-race carried by the bearing-member, balls rotatable between the ball-races, and a cap adjustable on the sleeve to retain the bearing-member in place with the ball-races in cooperative relation with the balls.
11. In a cone-holder support for winding machines, the combination with the drive-roll for rotating the cone, of a horizontal rod arranged parallel with the axis of the drive-roll, a pair of arms hingedly supported from said rod, means for rotatably supporting the cone-holder at the ends of said arms, and a hooked lever pivoted on one of the arms to adapt its extremity to ride on the periphery of the rod during the normal movement of the cone as its axis recedes from the drive-roll with the growth in the winding, said lever also adapted to hook around the rod to suspend the cone above the drive-roll when it is raised to a position beyond its normal range of movement.
12. In a cone-winding machine, the combination with the drive-roll for rotating the cone, of an arm pivoted to support one end of the cone to adapt the axis of the latter to recede from the drive-roll, means to displace said arm during the receding movement of the cone to shift the latter axially during the winding, a second pivoted arm for supporting the opposite end of the cone, and an extension hingedly mounted on said second arm to adapt it to swing laterally to provide for the axial displacement of the cone.
13. In a cone-winding machine, the combination with the drive-roll for rotating the cone, of a pivoted arm for supporting one end of the cone to adapt its axis to recede from the drive-roll during the growth in the winding, means to shift said arm laterally to displace the cone axially during the winding, a second arm for supporting the opposite end of the cone, a pivoted bearing for the second arm to adapt it to swing to accommodate the receding movement of the cone, and an extension hinged to the second arm to adapt it to swing laterally during the axial displacement of the cone.
14. In a cone-winding machine, the combination with the drive-roll for rotating the cone, of a pivoted arm for supporting one

end of the cone to adapt its axis to recede from the drive-roll with the growth in the winding, means for shifting said arm laterally to displace the cone axially during the winding, a second pivoted arm for supporting the opposite end of the cone, an extension hinged on the second arm to provide for its lateral movement during the axial displacement of the cone, and a spring bearing against the hinged extension to resist its lateral movement.

15. In a cone-winding machine, the combination with the rotating drive-roll and traversing thread-guide, of means for supporting the cone in contact with the drive-roll comprising an arm pivoted to rock on an axis at one side of the drive-roll, a tapered ring mounted to rotate on bearings at the end of the arm while allowing it to rock 20 slightly on its axis, a second arm mounted in opposed relation to the first arm and pivoted on an axis below the pivot of the first arm, an extension pivoted on the second arm to adapt its end to rock toward and 25 away from the first arm, a cup-member rotatable in a bearing at the end of the extension and formed with a cavity for receiving

the rounded apex-end of the cone-tube when its base end is fitted to the ring at the end of the opposite arm, and resilient-means acting 30 on the extension to maintain the cup-member pressing against the end of the cone-tube to hold its base in position on the bearing-ring.

16. In a winding machine, the combination with the rotating drive-roll and traversing thread-guide, of means for supporting the cone in contact with the drive-roll comprising a horizontal rod, arms pivotally supported from said rod to adapt their ends to 35 swing away from the drive-roll, a bearing-ring rotatably mounted on the end of one of the arms to adapt it to be inserted in the base end of the cone-tube, a cup-member rotatably mounted at the end of the opposite 40 arm to adapt it to receive the nose end of the cone-tube, and a hooked lever pivoted on one of the arms to adapt it to be hooked over the horizontal rod to hold the cone-supporting arms in raised positions above the drive-roll.

In testimony whereof I affix my signature.

GEORGE W. FOSTER.
